(57) **CLAIM**

I claim the ornamental design for a partial load trigger for a loop handle, as shown and described.

DESCRIPTION

FIG. 1 is a right-rear perspective view of the partial load trigger for a loop handle;

FIG. 2 is a right side view of the partial load trigger for a loop handle shown in FIG. 1;

FIG. 3 is a left side view of the partial load trigger for a loop handle shown in FIG. 1;

FIG. 4 is a front view of the partial load trigger for a loop handle shown in FIG. 1;

FIG. 5 is a rear view of the partial load trigger for a loop handle shown in FIG. 1;

FIG. 6 is a top view of the partial load trigger for a loop handle shown in FIG. 1; and,

FIG. 7 is a bottom view of the partial load trigger for a loop handle shown in FIG. 1.

The broken lines shown in the drawings represent unclaimed portions of the partial load trigger for a handle and form no part of the claimed design.
